UNITED STATES PATENT OFFICE

ROBERT C. ANGELL, OF PRINCE BAY, NEW YORK, ASSIGNOR TO THE S. S. WHITE DENTAL
MANUFACTURING COMPANY, A CORPORATION OF PENNSYLVANIA

DENTAL ENGINE HANDPIECE

Application filed August 20, 1928. Serial No. 300,657.

My invention relates particularly to that class of handpieces that are usually employed in connection with dental engines and in which the rotating parts include chuck mechanism arranged to detachably engage drills, burs, grinding tools, and such implements as are commonly employed in dentistry, and in which the tool actuating parts are belt driven and which are commonly known as all-cord handpieces.

The principal objects of my invention are to provide a dental engine handpiece of such simplified construction and arrangement that it may be so readily taken apart and assembled as to facilitate lubrication, cleansing and repair, and permit the parts to be conveniently sterilized.

Other objects of my invention are to provide a dental engine handpiece with exteriorly disposed adjusting means conveniently accessible for manipulation by the operator, whereby the outer casing or shaft may not only be secured in operative position, but may be adjusted to prevent end shake or chatter and to take up any wear on the spindle and its bearings.

My invention comprehends a tool driving spindle comprising a unitary hollow structure extending throughout the handpiece and affording a mounting upon which the driving cord pulley is directly mounted.

My invention also includes all of the various novel features of construction and arrangement as hereinafter more definitely specified.

In the accompanying drawings, Figure 1 is a side elevational view of a handpiece constructed in accordance with my invention, attached to a wrist joint connection; Fig. 2 is a central vertical longitudinal sectional elevational view of the handpiece structure shown in Fig. 1, the spindle being shown in elevation for convenience of illustration; Fig. 3 is an enlarged fragmentary sectional elevational view of the rear end of the handpiece shown in Figs. 1 and 2 taken on the line 3—3 in Fig. 2; Fig. 4 is a side elevational view of the split screw collar shown in section in Figs. 2 and 3 and in elevation in Fig. 1; Fig. 5 is a transverse vertical sectional view

of said split screw collar taken on the line 5—5 in Fig. 4; Fig. 6 is a longitudinal sectional view of the handpiece with the sheath removed, the tool and chuck rod being shown in elevation for convenience of illustration; Fig. 7 is a central vertical longitudinal sectional view, taken on the line 7—7 in Fig. 2, of the forward end of the handpiece shown in Figs. 1 and 2, the chuck rod being shown in elevation for convenience of illustration; Fig. 8 is a perspective view of the chuck rod and the collet through which it is longitudinally adjusted; Fig. 9 is a perspective view of the follower or plunger for effecting contraction or expansion of the chuck; and Fig. 10 is a perspective view of the split chuck shown in Figs. 6 and 7.

In said figures, the wrist joint frame 1 comprises the tubular bearing 2 in which the back or inner end portion of the spindle 3 is mounted for rotation, and which affords a forwardly projecting tubular telescopic support 5 for the expanded rear end portion 6 of the sheath 7.

Said spindle 3 is provided with an annular integral collar 9 forming the shoulder 10 which bears against the forwardly projecting end of that part of the bearing 2 which forms the sheath support 5 and which takes the axial working thrust of said spindle.

The forward end portion 12 of the spindle 3 is conically tapered and is rotatably fitted in the similarly tapered bearing 13 at the forward end of the sheath 7 which is provided with the axially disposed aperture 15 through which tools, such as the bur 16 shown in Fig. 6, may be inserted and withdrawn.

The rear end of the spindle 3 projects beyond the frame bearing 2 and is reduced to form the hub 17 for the driving cord pulley 19 which is prevented from relative rotation thereon by the flat surfaces 20, and which is secured thereon and forced against the shoulder 21 by the thumb screw or collet 22 having its shank 23 in threaded engagement with the threads 25 in the rear end of the bore 26 of the spindle 3.

The forward end of the bore 26 is conically tapered toward the axial tool receiving aperture 27 and affords a conical forward

seat 29 for the longitudinally split chuck 30 through the bore 31 of which the shank 32 of the tool 16 is extended, as shown in Fig. 6.

As best shown in Fig. 7, the split chuck 30 is normally expanded to receive the tool shank and has its opposite ends formed conical and respectively arranged to engage the conical seat 29 in the bore of the spindle 3 and the conical seat 35 in the forward end 10 of the follower or plunger 36 which is disposed for axial movement in the bore 26 and which is arranged to be forced forward to effect contraction of the chuck 30 by the axial adjustment of the chuck rod 37.

As best shown in Fig. 6, the chuck rod 37 extends through the collet 22 and is provided with the knurled head 39 by which it may be conveniently rotated to effect axial movement of the plunger 36 either by thrusting it 20 outwardly to cause contraction of the chuck 30 to engage the tool, or by withdrawing it inwardly to permit normal expansion of said chuck and consequent release of said tool.

The chuck rod 37 terminates in a rounded 25 forward end 40 so as to bear at an axial point on the plunger 36, and is maintained in concentric relation with the spindle bore 26 by the collar 41 which is integral with said chuck rod and preferably disposed adjacent to its 30 outer end.

The sheath 7 may for convenience be provided with a covering 43 of hard rubber, bakelite or other suitable material, that will not readily slip in the hand of the operator, 35 and the expanded rear end of the sheath terminates in a radially extended flange 45 which, when said sheath is in its working position, is spaced from the shoulder 46 formed on the frame by the threaded boss 47.

To the threaded boss 47 is secured the nut 50 having the knurled peripheral region 51 by which it may be conveniently rotated. Said nut is cooperative with the split collar 53 which is mounted to freely rotate on the 45 sheath 7 against the flange 45 in threaded engagement with said nut to effect axial adjustment of said sheath 7 on said spindle 3 with respect to said frame 1, whereby said sheath may be adjusted to vary the closeness 50 of fit of the conical or tapered bearing surfaces at the forward end of said sheath and spindle, or be backed off to permit the sheath to be removed therefrom.

The collar 53 may preferably be provided 55 with the transverse split 55, and the longitudinally disposed split 56 extended through the threads thereof and arranged to render the collar so resilient as to effect a binding action when engaged with the nut 50 to prevent its accidental displacement by reason of possible vibration of the handpiece structure.

From the foregoing, it will be obvious that 60 the inner adjustment of the sheath 7 is limited by the cooperation of the conical bearing surface 13 with the similarly tapered sur-

face on the spindle 3, so that any wear on said surfaces may be readily taken up by shifting the sheath inwardly and causing the flange 45 to more nearly approach the shoulder 46. This may be effected by merely rotating the collar 53 in threaded engagement with the nut 50.

My invention is advantageous in that the handpiece may be taken apart and the separate parts independently removed by the hands of the operator without the aid of tools; for instance, the sheath 7 may be removed by holding the frame in one hand while rotating the nut 50 with the split collar 53 between the thumb and finger of the other hand, and the spindle 3 may be removed from the frame 1 and the parts thereof separated therefrom by merely removing the thumb screw or collet 22 from said spindle.

Furthermore, a plurality of sheaths may be provided which may be interchangeably engaged with the spindle. Thus, it will be seen that a properly sterilized sheath may be readily substituted after operation upon each 90 individual patient.

I do not desire to limit my invention to the precise details of construction and arrangement as herein set forth, as it is obvious that various modifications may be made therein without departing from the essential features of my invention as defined in the appended claims.

Having thus described my invention, I 100 claim:

1. A dental handpiece comprising a frame, a spindle rotatably mounted in said frame and having a bearing surface, a sheath for said spindle having a complementary bearing surface forming a journal in which said spindle rotates, and exteriorly operable means conveniently actuated about the axis of said sheath arranged to adjustably vary the closeness of fit between said surfaces.

2. A dental handpiece comprising a frame, 110 a spindle rotatably mounted in said frame and having a tapered bearing surface, a sheath for said spindle having a journal bearing surface cooperative with the bearing surface on said spindle, and exteriorly operable means conveniently actuated in the direction of the axis of said sheath arranged to adjustably vary the closeness of fit between said surfaces.

3. A dental handpiece comprising a frame, 120 a spindle rotatably mounted in said frame and having a tapered bearing surface, a sheath for said spindle having a journal bearing surface cooperative with the bearing surface on said spindle and arranged to limit the inner movement of said sheath on said spindle, and exteriorly operable means adjustable coaxial with said sheath arranged to adjustably vary the closeness of fit between said surfaces.

4. A dental handpiece comprising a frame, a spindle rotatably mounted in said frame and having a tapered region, a sheath for said spindle having a bore provided with a surface cooperative with said tapered region and serving as a bearing therefor, and means embracing said sheath arranged to adjust it axially with respect to said frame and spindle and thereby compensate for wear on said bearing.

5. A dental handpiece comprising a frame having threaded means, a spindle rotatably mounted in said frame and having a tapered bearing region, a sheath for said spindle having a bore provided with a surface cooperative with said tapered bearing region and serving as a bearing therefor, and means coaxial with said sheath and cooperative with said threaded means arranged to adjust said sheath axially with respect to said frame and spindle and thereby cause said bearing surfaces to be engaged with any desired degree of closeness.

6. A dental handpiece comprising a frame, a nut in threaded engagement with said frame and having a threaded extension projecting forwardly, a spindle rotatably mounted in said frame and having a tapered region, a sheath for said spindle having a bore provided with a surface cooperative with said tapered region and serving as a bearing therefor, and a collar in threaded engagement with said threaded extension arranged to effect axial adjustment of said sheath with respect to said frame and spindle and thereby take up on said bearing.

7. A dental handpiece comprising a frame, a nut in threaded engagement with said frame, a spindle rotatably mounted in said frame and having a tapered region, a sheath for said spindle having a bore provided with a surface cooperative with said tapered region and serving as a bearing therefor, and having a flange at its inner end, and a collar rotatably mounted on said sheath in threaded engagement with said nut arranged to engage said flange and adjust said sheath axially with respect to said frame and spindle and thereby take up on said bearing.

8. A dental handpiece comprising a frame provided with threaded means, a spindle rotatably mounted in said frame and having a tapered region, a sheath for said spindle having a bore provided with a surface cooperative with said tapered region and serving as the bearing therefor and having a flange at its inner end, and a split collar rotatably mounted on said sheath in threaded engagement with said threaded means arranged to engage said flange and adjust said sheath axially with respect to said frame and spindle and thereby take up on said bearing.

9. A dental handpiece comprising a frame affording a bearing, a spindle rotatably mounted in said frame and having a collar

abutting against said frame, a driving cord pulley mounted on said spindle exterior to said frame, and a thumb screw threadedly engaged with said spindle tending to force said pulley forward and arranged to rotatably retain said spindle in said frame.

10. A dental handpiece comprising a frame affording a bearing, a spindle rotatably mounted in said frame bearing and having a shoulder abutting against said frame, a driving cord pulley mounted on said spindle, a collet in threaded engagement with said spindle, a tool engaging chuck within said spindle, a follower for said chuck, and a chuck rod in threaded engagement with said collet and arranged to actuate said chuck through its follower, said collet being the sole means for holding the spindle, driving cord pulley, chuck, follower and chuck rod together.

11. A dental engine handpiece comprising a frame, a spindle rotatably mounted in said frame provided with a shoulder and having a collar arranged to limit the inner movement of said spindle with respect to said frame, a driving cord pulley mounted on said spindle exterior to said frame, a thumb screw threadedly engaged with said spindle arranged to retain said driving cord pulley against said shoulder on said spindle and to prevent the forward displacement of said spindle, a sheath for said spindle having a bearing for the forward end thereof, and means arranged to adjustably engage said sheath toward said bearing to vary the closeness of fit of said bearing.

12. A dental engine handpiece comprising a frame, a spindle rotatably mounted in said frame and having a collar arranged to limit the inner movement of said spindle with respect to said frame, a driving cord pulley mounted on said spindle exterior to said frame, a thumb screw engaged with said spindle arranged to retain said driving cord pulley on said spindle, and to prevent the forward displacement of said spindle, a tool holding chuck disposed in the bore of said spindle, a plunger arranged to bear against the end of said chuck, and a chuck rod extended through said bore in threaded engagement with said thumb screw arranged to be rotated to force said plunger into operative engagement with said chuck.

13. A dental handpiece comprising a frame affording a bearing, a spindle mounted in said frame and having a shoulder bearing against said frame, a driving cord pulley mounted on said spindle exterior to said frame and means adjustably engaged with said spindle tending to force said pulley into position to rotatably retain said spindle in said frame.

In witness whereof, I have hereunto set my hand this 16th day of August, A. D. 1928.

ROBERT C. ANGELL. 130
